UNITED STATES PATENT OFFICE.

SEYMOUR G. SMITH, OF PLAINFIELD, NEW JERSEY, ASSIGNOR TO IDA M. SMITH, OF SAME PLACE.

EXPANSION-JOINT FOR BRICKWORK.

SPECIFICATION forming part of Letters Patent No. 552,787, dated January 7, 1896.

Application filed June 1, 1895. Serial No. 551,364. (No model.)

To all whom it may concern:

Be it known that I, SEYMOUR G. SMITH, of Plainfield, county of Union, State of New Jersey, have invented certain new and useful 5 Improvements in Expansion-Joints for Brick-work, of which the following is a full, clear, and exact description.

The object of the invention is to provide a new and improved expansion-joint for brick-work, whereby the latter may be subjected to 10 a high degree of heat without injury to the wall by the expansion and contraction of the brick.

The invention consists principally of a sheet 15 of non-combustible material interwoven transversely with the brickwork.

The invention also consists of certain parts and details and combinations of the same, as 20 will be fully described hereinafter, and then pointed out in the claims.

Reference is to be had to the accompanying drawings, forming a part of this specification, in which similar characters of reference indicate corresponding parts in both the figures.

Figure 1 is a side elevation of the improvement, and Fig. 2 is a plan view of the same.

A sheet A, of asbestos or other non-combustible material, is placed transversely in the wall B, built of brick, and the said sheet is interwoven with the brick as the different courses of brick are laid, so that joints are readily understood by reference to the figures. The sheets form a zigzag line both vertically 35 and transversely, and the side edges of the

sheets are preferably flush with the faces of the wall.

Sheets A are placed about three feet apart in a wall, so that the latter is divided into sections separated by the sheets of non-com- 40 bustible and sufficiently elastic material to compensate for the expansion of adjacent sections.

This joint is very serviceable in furnaces of all kinds, retorts, chimneys, and all brick- 45 work subjected to heat.

Having thus described my invention, I claim as new and desire to secure by Letters Patent—

1. An expansion joint for brick-work, consisting of a sheet of non-combustible material transversely interwoven with the brick-work, substantially as shown and described. 50

2. An expansion joint for brick-work, consisting of a sheet of non-combustible material, such as asbestos, and interwoven transversely with the brick-work and breaking joint with the layers of brick, substantially 55 as shown and described.

3. An expansion joint for brick-work, consisting of a sheet of non-combustible material arranged transversely in the brick-work and in an approximately zig-zag line according to the joints of the bricks in the different layers. 60

SEYMOUR G. SMITH.
